UNITED STATES PATENT OFFICE

HENRY FANTEL, OF NEW YORK, N. Y.

COMBINATION LAMP AND CLOCK SUPPORT

Application filed December 19, 1930. Serial No. 503,541.

This invention relates to time keeping devices, such as clocks, and more particularly to their supports, the structure being specially adapted for use in connection with a night lamp.

The difficulty encountered in ascertaining the time at night is well known and overcome only by maintaining an objectionably strong light or the inconvenience of causing 10 a lamp to glow while the hour is observed, all of which are annoying to an invalid or tired person in the room.

While it is known that clock dials have been made with luminous numerals, the light 15 giving properties are ordinarily evanescent, gradually weakening until total failure occurs.

It is also known that a steady but dim light in a sick room or sleeping chamber may 20 be maintained indefinitely without discomfort or inconvenience to the occupant.

It is therefore an object of the present invention to utilize the light rays of a lamp by causing a portion of them to pass through 25 the translucent dial of a clock carried by the lamp in such manner that the exact time can be read without difficulty from even a remote point.

A further feature is in the provision of 30 a translucent shade, supported directly by a lamp, preferably adjustable as the effulgence of its rays, the shade having a part arranged as a dial, and carrying a clock-works mechanism including hands to pass over the 35 dial in the usual way.

Another aim is to produce a useful attachment of the class described capable of congruous application to an electric bulb direct 40 or to a transparent guard used as a chimney for an electric lamp or a lamp of the oil burning type, the invention residing in the clock support.

These advantageous objects are attained 45 by the novel design, construction and arrangement of parts hereinafter described in detail and illustrated in the accompanying drawings, constituting a material part of the disclosure, and in which:

Fig. 1, is a top plan view of an embodi-

ment of the invention showing its application.

Fig. 2, is a front elevational view of the same.

Fig. 3 is a partial vertical sectional view 55 taken through the shade, showing a clock attached, and drawn to an increased scale.

Referring in greater detail to the drawings the numeral 5 designates in general the base, of an ornamental, semi-portable hand 60 lamp, patterned in the similitude of an oil burning lamp, provided with a handle 6 and pseudo wick adjuster 7, above which is carried a socket 8 to receive a chimney 9.

In the present case an electric current is 65 entered through a conductor 10 to pass to an incandescent bulb 11 disposed within the chimney 9 and provided with a switch, actuated by the knob 7, by which the lamp is controlled, preferably giving full, moderate or 70 dim light as may be desired.

The chimney shown is of the usual shape, being cylindrical at its upper portion, blending into a bulbous main portion and then contracted to engage closely in the socket 8. 75

Engaging the chimney, at the upper part of its bulbous portion, is a ring 12 rigidly connected to a similar but slightly larger ring 13, disposed thereabove, by a plurality of spacing bars 14.

The upper ring 13 is enveloped in a thin casing 15 by which is attached the upper edge of a conical or polygonal pyramidal frustrom shade 16, its broad base extending downwardly to enclose the bulbous portion of the chimney.

The shade may be of any suitable material, opaque if preferred, except for a panel portion as later seen.

The lower edge of the shade is held 90 clamped to a ring 17 by an enclosing casing 18 holding the material taut.

A panel-like portion 20, oval in plan view, as shown in the drawings or of any shape desired in practice, and of any diameter within the capacity of the shade, is translucent and provided at its marginal edge with a series of marks 21, indicating minutes arranged in groups of five, while adjacently therewith are numeral 22 indicating hours. 100

At the center of the dial thus formed is a disc 23 through which extends the spindles 24 of a clock-works mechanism 25, secured in any suitable manner to the interior of the shade, and actuating hands 26—27, respectively minute and hour, which operate over the dial.

In order to maintain the shade in equilibrium a counterweight 28 may be attached to the interior of the shade at a point opposite the clock.

It will be obvious that the ring 12 may be applied directly to a naked bulb in case the chimney is not required, and that other modifications and changes may be made within the scope of the appended claims and which do not require the exercise of invention.

Having thus described my invention, what I claim as new and desire to secure by Letters Patent, is:

1. The combination of a clock having an outwardly flanged translucent dial over which the clock hands travel, said dial constituting an integral part of an annulus, a lamp, and means on said annulus to engage said lamp circumjacent whereby light may pass through said dial.

2. The combination with a clock-works mechanism, a conical annulus carrying said mechanism, a transparent dial integrally formed on said annulus relative to said mechanism, and means to engage said annulus to surround a lamp so that light therefrom may pass through said dial.

3. In combination with a lamp shade, of a clock-works fixed to the inner surface of said shade, and a dial for said clock-works integral with the shade, said dial being translucent and extending circumjacent beyond the space occupied by said clock-works.

4. In combination with a lamp shade, of a clock-works fixed to the inner surface of said shade, and a dial for said clock-works integral with the shade, said dial being translucent and extending circumjacent beyond the space occupied by said clock-works and a counterbalance for said clock-works fixed to said shade.

5. In combination with a conical shade for a portable lamp, of a clock-works fixed within said shade on one side, a counterbalance on the opposite side, a transparent panel in said shade to register with said clock-works, a clock dial inscribed on said panel, said panel being of greater diameter than said clock-works, and hands actuated over said dial by said clock-works.

Signed at New York, in the county and State of New York, this 13th day of November, 1930.

HENRY FANTEL.
